UNITED STATES PATENT OFFICE.

ZEBINA EASTMAN, OF CHICAGO, ILLINOIS.

IMPROVEMENT IN RAILWAYS.

Specification forming part of Letters Patent No. 58,621, dated October 9, 1866.

To all whom it may concern:

Be it known that I, ZEBINA EASTMAN, a citizen of the United States of America, but at present the United States consul for and residing at Bristol, in the county of Gloucester, in England, have invented a new and useful Improvement in the Running-Gear of Carriages, Wagons, and Cars; and I do hereby declare that the following is a full and exact description thereof, reference being had to the accompanying drawings, and to the letters of reference marked thereon.

My invention consists in constructing the working part of carriages and wagons with movable and self radiating and adjusting axle-trees, to adapt themselves and the carriages to curves and circles or straight lines.

For my four-wheel carriages or cars I mount upon each of the two axle-trees a circular rim or bed-piece, which is firmly bolted to the axle-trees, upon which the body of the carriage rests, and on which it turns, assisted by friction-rollers when necessary, as the axle-tree turns or oscillates while the carriage is making a circle. I secure the carriage with a king-bolt through the center of each axle-tree, and which also forms the center of this supporting ring or bed-piece or table on which the carriage rests. I ease the carriage by an india-rubber pad or spring, through which the king-bolt passes, or by the use of other springs attached to the friction-rollers. I connect the two axle-trees by a reach or connecting-rod in the center, through which the king-bolt passes. I also connect the axle-trees with another reach or connecting-rod, which I attach to an ear-piece near one end of the axle-tree, and pass it diagonally or transversely across the center reach to a like fastening on the opposite end of the other axle-tree. Thus, when one axle-tree is moved in either direction to adapt itself to the curve in the rails, the opposite end of the other axle-tree will be moved by this transverse rod in like manner, and thus by the force of the propelling power, by this combination, whenever one pair of wheels or an axle-tree moves in a circle the other pair radiates to the same circle or curve, and returning again to parallel lines when the carriage is drawn upon straight, and thus no more friction is produced in traveling round

corners or even complete circles than when running on a straight line.

Figure 7 is a view in plan, and Fig. 8 a view in side elevation, of the working part of a four-wheel carriage or wagon with this improvement applied.

dd are the tables or bed-pieces, to which the axles *ee* are united, and on which the wheels *ff'f'f'* are free to rotate. *gg* are the king-bolts, by which the carriage or wagon (not shown) is or may be attached thereto. *h* is the connecting-rod or reach uniting the axles *ee*, and loosely connected thereto. *i* is the rod or transverse reach uniting the tables *dd*. When the carriage or wagon travels in a straight line, or nearly, as shown in Figs. 7 and 8, the axles remain parallel to one another, or nearly so, as seen in those figures; but at a curve or bend of the tram, as shown in Fig. 9, the wheels radiate and adapt themselves thereto, no matter how great or how little the curve may be.

I construct my carriages of six wheels and three axle-trees, as follows: The plan of this is given in Fig. 10. I connect the axles *ee* with center reaches, *bb*, as in the carriage before described; but I joint the reaches at the connection with the middle axle-tree, *y*, so as to allow that to oscillate across the carriage-body. The central axle-tree, *y*, carries a quadrant-shaped frame, *r*, provided with teeth or cogs, with corresponding teeth on a similar frame on the fore and hind axle-tree, as the case may be, *ss* forming a segment of gear-wheels, which are bolted to the front and rear axle-trees and united with each in gear, as shown. I connect the front and rear segments with transverse reaches *ii*. Thus, by the combination of the segments and reaches, when the carriage moves and turns upon a circle the axle-trees all radiate by a simultaneous action, as in the case of the two-axle-tree carriage before described, and the line of each of the three axle-trees points to a common center of a circle.

The carriage frame or body is attached to the running-gear by king-bolts and elastic springs through the reaches, as seen at *oo*, and is also supported and kept in a steady and easy position by semi-elliptic or other springs *vv* on the sides of the carriage, resting upon

the middle axle-tree. The movement of the end axle-trees into a curve causes the middle axle-tree to traverse endwise across the frame of the carriage, the line of which is always directly square with the carriage.

Having thus fully described my invention, what I claim as new, and desire to secure by Letters Patent, is—

1. The axles *e e*, each constructed in one piece, in combination with the tables or bed-pieces *d d*, connecting-rod or reach *h*, and transverse reach *i*, the whole being constructed, arranged, and operated substantially in the manner and for the purpose set forth.

2. The axles *e e y*, in combination with the reach *b*, toothed frames *r s s*, and transverse reaches *i i*, the whole being constructed and operated substantially in the manner and for the purpose set forth.

Signed at Bristol, England, June 14, A. D. 1866.

ZEBINA EASTMAN.

In presence of—

SIDNEY C. EASTMAN,
WILLIAM BAKER.
